UNITED STATES PATENT OFFICE.

GOTTLIEB L. E. KLINGBEIL, OF OMAHA, NEBRASKA.

SPRING SPREADER.

Application filed September 7, 1922. Serial No. 586,776.

To all whom it may concern:

Be it known that I, GOTTLIEB L. E. KLINGBEIL, a citizen of the United States, residing at Omaha, in the county of Douglas 5 and State of Nebraska, have invented certain new and useful Improvements in Spring Spreaders, of which the following is a specification.

This invention relates to spring spreaders for vehicle springs and more particularly for automobile springs. It is a well known fact that vehicles and particularly automobiles are rendered "easy riding" and many objectionable squeaks are eliminated if the 10 springs are properly lubricated from time to time. However, this work is frequently neglected by the owner of the automobile because of the difficulty of separating the leaves of the springs. For the same reason 15 the cost of having this work done at a garage is considerable. The object of the present invention is to provide a spring spreader constructed in such manner that by a single movement of an operating handle all of the leaves of a spring will be 20 separated simultaneously and automatically held in such separated condition during the time that they are being lubricated or otherwise worked upon.

25 Further objects and advantages of the invention will be set forth in the detailed description which follows:

In the accompanying drawing:

Fig. 1 is a side elevation of a spring spreader constructed in accordance with the invention;

Fig. 2 is a detail view of the upper end of one of the standards looking in a direction at right angles to Fig. 1 and illustrating a wedge assembly hereinafter described;

Fig. 3 is a perspective view of one of the wedge elements; and

Fig. 4 is a detail view of the complete wedge assembly.

Like numerals designate corresponding parts in all of the figures of the drawing.

The spring spreader of the present invention comprises a base 5 in which a tilting block 6 is mounted upon trunnions 7. Substantially vertical standards 8 and 9 are pivoted in the tilting block at 10 and 11. The upper ends of these standards are moved toward and from each other by a self locking mechanism which consists of a transverse shaft 12 mounted in upstanding portions 13 of the tilting block 7 and pro-

vided with an angular end 14 for the reception of a handle or other suitable tool by which a partial turning movement may be imparted to the shaft. The shaft 12 carries cranks 15 to the outer ends of which bent links 16 and 17 are pivotally connected at 18 and 19, respectively. The outer ends of these bent links are pivotally connected at 20 and 21 to the lower ends of levers 22 and 23. These levers, in turn, are pivotally connected at 24 and 25 to the standards and said levers at their upper extremities are pivotally connected at 26 and 27 to the cross links 28 and 29, respectively. The link 28 is pivotally connected at 30 to the standard 9 and the link 29 is pivotally connected at 31 to the standard 8. Thus it will be seen that if a turning movement be imparted to the shaft 12 by the application of the proper tool to the angular head 14 of said shaft and the bent links 16 and 17 be thrown to the position illustrated in Fig. 1 the standards will be 60 forcibly moved toward each other due to the levers 22 and 23 acting directly upon the standards at pivot points 24 and 25 and upon the opposed standards through the crossed links 28 and 29. It will further be seen that the standards will remain in the 65 position to which they are moved when they are brought forcibly together due to the fact that with the parts in the position illustrated in Fig. 1 a line drawn from pivot point 19 to pivot point 21 lies below the center of the shaft 12. In other words 70 that portion of the crank 15 which acts upon the link 17 has been moved to past center position and the same is true with respect to link 16 and that part of the crank which acts upon it. The upper portions of the standards are slotted, as indicated at 35 for the reception of wedge assemblies, said wedge assemblies being bodily 75 insertable in the upper portions of the standards as units. The purpose of arranging the parts in the manner described is to render it possible to easily and quickly place different wedge assemblies in position according to the size, width and thickness of the springs which are to be acted upon. Cars of many different makes are brought to public garages to have their springs lubricated. Thus it is necessary to provide, 80 in an article of this nature, means for readily adapting it to take care of the different sizes of springs. To this end I pro-

vide the wedge assemblies consisting of bolts 36 having handles 37 at their upper ends. These bolts pass through elongated openings 38 formed in a plurality of wedge elements 39. A spring 40 bears between a collar 41 and a plate 42 and this plate is adapted to rest upon the tops of the standards and to span the slotted portions 35 thereof. The wedge elements 39 are provided with shoulders 43 which rest against the front faces of those portions of the standards which lie upon opposite sides of the slotted portions thereof and which take the rearward thrust of these wedge elements and relieve the bolts of this strain. The lower ends of the bolts are reduced, as indicated at 44 to enter openings 45 formed in the standards. A plate 46 having a rounded upper face 46a is threaded at 47 upon the lower portion of the bolts and the rounding of the upper face of this plate facilitates tipping movement of the wedge elements as they individually seek to come to a position of rest with their pointer inner ends engaged in the grooves between the leaves of the springs to be spread. I preferably dispose a spring 48 between plate 46 and the bottom of the bifurcated portion of the standards. By thrusting bodily downward upon the top of these bolts the group of wedges may be given a limited vertical movement as a whole to bring about a coarse adjustment of the vertical position of the several wedge elements. Capability of the wedge elements of individual movement permits the several wedge elements to seek a position of rest with their pointed inner ends engaging in the grooves between the leaves of the springs as hereinbefore stated.

It is to be understood that the invention is not limited to the precise construction set forth but that it includes within its purview whatever changes fairly come within either the terms or the spirit of the appended claims.

Having described my invention what I claim is:

1. A device of the character described, comprising a pair of elements movable toward and from each other and individual wedge assemblies for each of said elements removably mounted thereon, each of said wedge assemblies comprising a group of individually movable wedges and means for holding them in assembled relation when removed.

2. A device of the character described, comprising a pair of elements movable toward and from each other, self-locking means for locking these elements in position when drawn toward each other, and removable wedge assemblies upon each of said elements, each of said wedge assemblies

comprising a group of individually movable wedges and means for holding them in assembled relation when removed. 65

3. A device of the character described, comprising a supporting base, a pair of standards pivoted thereon, a transverse shaft pivoted thereon, a pair of cranks carried by said shaft, links pivotally connected to the outer ends of said cranks, levers pivoted to the said standards and to the outer ends of said links, and crossed links pivotally connected to the upper ends of said levers and to the opposed standards. 70

4. A structure as recited in claim 3, wherein in the throw of the cranks is such that the first-named links are moved to past center 80 position when the standards are drawn toward each other to thereby cause the structure to be self locking.

5. A structure as recited in claim 3, wherein in the upper ends of said standards are 85 slotted and bodily removable wedge assemblies seated in the slotted portions of said standards.

6. A structure as recited in claim 3, wherein in the lower portions of the standards are 90 pivoted upon a laterally tiltable block.

7. A device of the character described, comprising a supporting base, a laterally tilting block trunnioned thereon, a transverse shaft supported upon the laterally tilting block, oppositely extending cranks carried by said shaft, bent links pivotally connected to the outer ends of said crank, levers pivotally connected to the outer ends of said links, standards pivoted to move 100 toward and from each other upon the laterally tilting block, said levers being likewise pivoted to said standards intermediate the ends of said levers, crossed links to which the upper ends of said levers are pivoted, the opposite ends of said links being pivoted to the opposed standards, and individually adjustable wedge elements mounted in the upper portions of said standards. 105

8. In combination, a supporting element, a wedge assembly comprising a supporting bolt, a plurality of wedge elements upon said bolt mounted in the supporting element, said wedge elements having elongated openings formed therein through which said bolt passes, a block upon the bolt beneath said wedge elements, said block having a rounded upper face, and spring means for mounting said bolt for yielding 115 vertical movement with respect to the supporting element. 120

In testimony whereof I affix my signature in the presence of two witnesses.

GOTTLIEB L. E. KLINGBEIL.
